UNITED STATES PATENT OFFICE

ALBERT D. FIELD, OF NEW YORK, N. Y.

CURTAIN-POLE COVERING.

SPECIFICATION forming part of Letters Patent No. 378,085, dated February 21, 1888.

Application filed November 21, 1885. Serial No. 183,559. (No model.)

To all whom it may concern:

Be it known that I, ALBERT D. FIELD, of New York, in the county of New York and State of New York, have invented certain new and useful 5 Improvements in Curtain-Pole Coverings; and I do hereby declare the following to be a full, clear, and exact description of the invention, such as will enable others skilled in the art to which it appertains to make and use the same.

10 My invention relates to an improvement in window-pole coverings.

The object is to provide a covering capable of being extended or contracted to cover a greater or lesser portion of a pole, as may be desired.

15 With this end in view, my invention consists in certain features of construction and combinations of parts, as will be hereinafter fully described, and pointed out in the claim.

20 In the accompanying drawings, Figure 1 represents a pair of covering-sections in position in front of a pole. Fig. 2 is a transverse section through one of the covering-sections; and Fig. 3 represents one of several devices for 25 rendering the covering extensible.

A represents covering-pieces made of any suitable material and adapted to cover all or a portion of the curtain-pole B to present an ornamental and showy finish which covers the 30 joints or any defects or blemishes in the pole. These pieces A are secured, preferably, by

means of pins or bolts a to the front edge of the pole-bracket C.

Now, in order to admit of an adjustment to suit different widths of windows—or, in other words, different lengths of poles, to cover more or less of the latter—the covering pieces are formed in sections, as shown in detail in Fig. 3. As represented in this figure, the edges c' of the female section are bent over, forming 40 grooves adapted to receive the edges d', respectively, of the male section. This construction, however, is only one of the several feasible devices for extensibly securing the covering-pieces and at the same time admitting of 45 the free sliding of the rings or other sliding device.

Having fully described my invention, what I claim as new, and desire to secure by Letters Patent, is—

50 The combination, with a curtain-pole and two supporting-brackets, of two extensible covering-pieces, one secured to each bracket, substantially as set forth.

In testimony whereof I have signed this specification in the presence of two subscribing witnesses.

ALBERT D. FIELD.
